UNITED STATES PATENT OFFICE.

JOSEPH RAKONICK, OF ST. LOUIS, MISSOURI.

ARCH-SUPPORTING SHOE.

Application filed August 11, 1924. Serial No. 731,481.

To all whom it may concern:

Be it known that I, JOSEPH RAKONICK, a citizen of the United States, residing at St. Louis, in the State of Missouri, have 5 invented certain new and useful Improvements in Arch-Supporting Shoes, of which the following is a specification.

This invention relates to improvements in shoe constructions, and particularly to 10 a shoe having a built-in arch supporting structure.

The invention comprehends the provision of a built-in arch supporting structure in a shoe, so that the manufacturer of a shoe may 15 build the standard shoe sizes for a retail dealer, for supply to the trade, having an arch supporting structure therein, which, in its manufactured form, as delivered to the retail dealer, will be of a substantially re- 20inforced construction throughout the arch portion of the shoe and will be provided with a permanent arch supporting strip secured to the insole of a shoe, and of a construction so as to provide a primary sup- 25port for the main arch of the foot, when the shoe is being worn. This strip in pro- 30viding a main arch support is of such a character that it is of the proper height or thickness for providing the proper curva- 35ture and support for an arch of minimum height or curvature. As the normal arches of the feet vary in different people in the height and degree of curvature, both longitudinally and transversely of the foot, 40 it is substantially impossible to manufac- 45ture shoes having an arch support incor- 50porated therein in the standard sizes, which will be adapted for properly supporting, in the normal and proper relation, the par- 55ticular arch of the person purchasing the shoe or shoes. It has been found, however, that the shoes may be constructed with a permanent or main arch support as an integral part of the shoe, having a minimum 60dimension for providing a primary arch support. It has also been found that this primary integral arch support, constructed in a shoe, also serves to provide the first step for treating flat feet and broken arches, 65 in order to restore the proper normal arch of the person's foot.

The invention therefore comprehends the provision of a main and primary arch sup- 70port adapted to be constructed in a shoe,

in the making thereof, in standard sizes for 55 the trade, in such a manner that a pocket will be provided between the strip and the top side of the insole, so that supplementary arch supporting inserts may be inserted on top of the inner sole and beneath the 60 strip forming the primary arch support for raising the height of the support in the shoe and for varying the curvature both longitudinally and transversely thereof, in order to adapt it to support the higher normal 65 arches of particular types of feet, and also for providing peculiar adjustments thereof to fit the abnormal types of feet.

With the above considerations in view, the invention also comprehends the provi- 70sion of a built-in arch support in a shoe wherein the inner sole of the shoe is provided with an extension on the inner side thereof, extending throughout the length of the arch portion or shank of the shoe, and a primary 75 or main arch supporting strip secured to the inner sole at the forward and rear ends thereof and extending transversely across the insole throughout the width thereof and overlying the extension thereon, and pro- 80viding a pocket on top of the insole open at the sides, and adapted to receive sup- 85plementary arch supporting inserts, said strips having the central portion of sub- 90stantial thickness, and having a gradually reduced thickness toward the free edges of the same, in order to provide a primary arch support of minimum height and curvature.

The invention also includes other objects and improvements in the details of construc- 95tion and arrangement of the parts, which are more particularly pointed out in the following description and claims directed to a preferred form of the invention, it being understood, however, that various changes 95 may be made in the specific construction and arrangement of these parts without departing from the scope and spirit of the invention as described and claimed.

In the drawing, forming a part of this 100 application,

Figure 1 is a vertical longitudinal sec- 105tional view, through a shoe constructed accord- 110ing to this invention.

Figure 2 is a transverse sectional view 105 through the shank or arch portion of the shoe taken on the line 2-2 of Figure 1.

Figure 3 is an enlarged detail perspective

view of the inner sole of the shoe and the primary arch supporting strip attached thereto.

In the shoe construction illustrated in the drawing, 1 indicates the outer sole, 2 the upper, and 3 the inner sole, all united in any desired and well-known manner now used in the art, in the construction of the shoe.

10 In the construction of the shoe according to this invention, the insole 3 is formed with an extension 4, on the inside of the arched portion thereof, which is adapted to extend upwardly and lie against the inside of the upper of the shoe as clearly illustrated in Figures 1 and 2, the extension being shaped on a last during the construction of the shoe, and the application of the upper and outer sole in the usual and well known manner.

15 20 The outer edge of the extension 4 is of substantially the arcuate curvature illustrated in Figures 1 and 3, and is of gradually decreasing thickness toward the free edge portion and terminates in a feather edge as indicated at 5. A main or primary arch support is provided in the shoe in the form of a strip 6, which is positioned in the central portion of the shoe over the arch or shank portion and which extends transversely across the top portion of the inner sole and overlies the extension 4 thereon.

25 30

This strip is secured to the inner sole along the forward and rear edges as indicated at 7, by which it is incorporated as a permanent part of the shoe. The strip has a major thickness in its central portion as indicated at 8, and from which it is of gradually reducing thickness to the free edges, as clearly illustrated in Figures 1 and 2 of the drawings. The portion overlying the extension 4 terminates in a feather edge 9, so that the surface of the same will comfortably fit the contour of the foot of the wearer. From an inspection of Figures 1 and 2, it

40 45 50 55 60 65

will be seen that this portion 8, of major thickness, lies along the transverse center line of the strip and the shoe, and that it is disposed at one side of the inner sole of the shoe, as clearly shown in Figure 2, so that it will be positioned in the proper location, for giving the proper contour to the inner surface of the shoe, so that it will have the proper contour of the normally low arch, which is characteristic of some feet. This strip 6 forms a pocket, in cooperation with the insole 3 on the bottom thereof, which is open at both sides of the shoe, and which is adapted to receive supplemental arch supporting inserts 9, which it may be found desirable to use, in connection with persons wearing shoes constructed in accordance with this invention, wherein they have the normally high type of arch in their feet.

It will be seen that in providing a pocket

65 which is open at both sides, insertions may

be made on top of the insole within the pocket, for raising the arch portion on the primary arch supporting strip throughout the entire width of the insole and the extension 4 formed thereon.

In the making of shoes according to this invention, the primary arch supporting strip 6 is constructed as a permanent part of the shoe when the same is manufactured and forms an arch supporting shoe for what may be called a normally low arch, so that at the time the shoes are sold to the customer by a retailer, the proper inspection of the customer's feet may be made, in order to determine whether he has a low arch which may be perfectly normal in its proper form, in which case the strip 6 provides the proper support, or whether he may have some abnormal form of arch or a higher type of arch, in which case supplementary arch supporting inserts, such as those indicated at 9 are placed in the pocket formed on top of the inner sole, in order to give the proper height and contour to the strip 6 for adapting it to the peculiar type of arch of the customer.

In the event that the customer has broken arches or is flat footed, the arch supporting strip 6 forms the first step in the treatment to be accorded to the purchaser for restoring the arches to the proper form and contour, so that he is sold a pair of shoes which merely have the main arch supporting strip therein, so that the arches will be slightly raised to the position of the normal minimum low arch, during which time the arch will be returned toward its normal state, in order that the bones of the feet may be gradually replaced to their normal position without undue discomfort to the wearer, following which a further treatment is given the customer for restoring his arches to their normal state by placing supplemental arch supporting inserts in the pocket formed on top of the insole by the strip 6, which may be of any desired shape and thickness or number, in order to produce the support for the arch of the foot, of the customer, at the proper place, in order that his arches may be restored to their normal and proper form.

It will thus be seen that the present invention provides an improved construction in shoes, wherein an arch support is incorporated in the structure of the shoe, which is adjustable, and which may be made in the usual standard sizes of shoes, so that the proper compensation can be made in the arch supporting structure to adapt it to the varying types of arches of the purchasers of such shoes, which can be effected at the time of sale of the shoes to a purchaser, and which will not only correct faulty arches and restore them to their normal shape, but which will also prevent falling arches or

other forms of defective feet now generally known to science.

What is claimed is:

1. A shoe having a built-in adjustable arch support comprising an outer sole, an inner sole, and an upper secured together in associated shoe forming relation, said inner sole having an extension on the inner side thereof throughout the arched portion of the shoe extending upwardly along the inside of the upper for reinforcing the arch of the shoe and forming a base for the arch supporting structure, and an arch supporting strip superposed on the inner sole transversely over the arched portion thereof and the extension on said sole, said strip being secured to said inner sole at the forward and rear edges and forming a pocket on top of the inner sole throughout the arch portion of the shoe open at the side and adapted to receive supplemental arch-supporting inserts on top of said inner sole and extension. 30
- 10 the shoe extending upwardly along the inside of the upper for reinforcing the arch of the shoe, and an arch supporting strip superimposed on the inner sole transversely thereof over the arch portion of the sole and the extension thereon, said strip being secured to said inner sole at the forward and rear edges and forming a pocket on top of the inner sole throughout the arched portion and open at both sides of the shoe to 35 adapt it to receive supplemental arch supporting inserts on top of said inner sole and extension. 40
- 15 20 25 2. A shoe having a built in adjustable arch support comprising an outer sole, an inner sole, and an upper secured together in

associated shoe forming relation, said inner sole having an extension on the inner side thereof throughout the arch portion of the shoe extending upwardly along the inside of the upper for reinforcing the arch of the shoe and forming a base for the arch supporting structure, and an arch supporting strip superposed on the inner sole transversely over the arched portion thereof and the extension on said sole, said strip being secured to said inner sole at the forward and rear edges and forming a pocket on top of the inner sole throughout the arch portion of the shoe open at the side and adapted to receive supplemental arch-supporting inserts on top of said inner sole and extensions, said strip being further formed of substantial thickness along the transverse center line thereof and in the central portion, and of gradually decreasing thickness 45 toward the free edges of the strip terminating at said edges in a feather edge.

In testimony whereof I affix my signature.

JOSEPH RAKONICK.
